Carpets

No. 5,644.

Mar. 12-1872

UNITED STATES PATENT OFFICE

ARTHUR M. KING OF KIDDERMINSTER, ENGLAND, ASSIGNOR TO HENRY JECKS DIXON & SONS, OF SAME PLACE.

DESIGN FOR A CARPET-PATTERN.

Specification forming part of Design No. 5,644, dated March 12, 1872.

To all whom it may concern:

Be it known that I, ARTHUR MAZEPPA KING, of Kidderminster, county of Worcester, England, have invented a new and original Design for Carpets; and I do hereby declare that the following is a full, clear, and exact description thereof, which will enable others skilled in the art to make and use the same, reference being had to the accompanying photographic illustration forming part of the specification.

This invention relates to a new design for an ornamental center figure of a carpet, said figure A approximating a square outline with scalloped edges a a. In its middle is a small rosette, b, said rosette being also in the center of a cross, c, which divides the figure A into four fields, d. At the corners these fields are reduced by curved lines e.

I claim as my invention—

The design of the figure A in a carpet, as shown.

ARTHUR MAZEPPA KING.
